UNITED STATES PATENT OFFICE.

THOMAS S. POWERS, OF ESSEX, CONNECTICUT.

DESIGN FOR A COFFIN-HANDLE.

SPECIFICATION forming part of Design No. 15,563, dated November 18, 1884.

Application filed September 3, 1884. Term of patent 7 years.

To all whom it may concern:

Be it known that I, THOMAS S. POWERS, of Essex, in the county of Middlesex and State of Connecticut, have invented a new and Improved Design for a Coffin-Handle, of which the following is a full, clear, and exact description.

My design for a coffin-handle consists in an ornamental configuration of the handle at different points in its length, substantially as hereinafter described, and shown in the accompanying drawing, which represents a longitudinal view of a coffin-handle embodying my design. The handle throughout is of a rounded configuration in transverse section. Its center portion consists of two meeting ovolos, *a a*, joined by flutes *b b*, terminating at their outer ends in circular grooves or creases. The remainder of the handle in its opposite directions is of similar shape, each of such portions consisting of an elongated longitudinal concave, *d*, having an enlarged diameter at its outer end, next adjacent to which is a half-round circular grooved molding, *e*, bound in an outward direction by a circular band or fillet, *f*, outside of or beyond which is an ogee molding, *g*, terminating in an outer circular ovollo, *h*. Beyond or outside of this is an elongated cylindrical portion, *i*, the outer end of which is ornamented by an ovollo and ogee molding, *h' g'*, having a reverse position

to the ogee and ovollo molding *h g*, and bounded at its outer end by a circular fillet or band, *f'*, circular grooved molding *e'*, a band, *k*, outwardly-tapering concave moldings *l m*, all in 35 regular order, as described, and terminating in a tapering tip, *s*, of an ogee and rounded profile with straight conical extremity.

Having thus fully described my invention, I claim as new and desire to secure by Letters 40 Patent—

The within-described design for a coffin-handle having a rounded configuration throughout its length, which consists of two meeting ovolos, *a a*, in its center, joined by flutes *b b*, 45 and opposite longitudinal extensions, each composed of a longitudinal concave, *d*, having an enlarged diameter at its outer end, a half-round circular grooved molding, *e*, a band or fillet, *f*, reverse ovollo and ogee moldings *g* 50 *h g' h'*, with a straight cylindrical portion, *i*, between them, a circular band or fillet, *f'*, circular grooved molding *e'*, a band, *k*, outwardly-tapering longitudinal concaves *l m*, and a tapering tip, *s*, of an ogee and rounded 55 profile with straight conical extremity, as shown.

THOMAS S. POWERS.
